(57) **CLAIM**

The ornamental design for a vaporization device, as shown and described.

DESCRIPTION

FIG. 1 is a back perspective view of a vaporization device showing a first embodiment of our new design;
FIG. 2 is a side view of the design of FIG. 1;
FIG. 3 is a top view of the design of FIG. 1;
FIG. 4 is a front view of the design of FIG. 1;
FIG. 5 is a back view of the design of FIG. 1;
FIG. 6 is a front perspective view of the design of FIG. 1;
FIG. 7 is a back perspective view of a vaporization device showing a second embodiment of our new design;
FIG. 8 is a side view of the design of FIG. 7;
FIG. 9 is a top view of the design of FIG. 7;
FIG. 10 is a front view of the design of FIG. 7;
FIG. 11 is a back view of the design of FIG. 7; and
FIG. 12 is a front perspective view of the design of FIG. 7. The broken lines in the drawings depict portions of the vaporization device that form no part of the claim.
